(57) **CLAIM**

The ornamental design for a bathtub sticker, as shown and described.

DESCRIPTION

FIG. 1 is a perspective view of a bathtub sticker;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partial enlarged view of the area labeled “8” in FIG. 1 thereof;

FIG. 9 is a partial enlarged view of the area labeled “9” in FIG. 2 thereof; and,

FIG. 10 is a partial enlarged view of the area labeled “10” in FIG. 4 thereof.

The dash dot dash lines in FIGS. 1, 2, 4, 8, 9 and 10 are for the purpose of depicting the boundary lines of the enlarged view and form no part of the claimed design.
